UNITED STATES PATENT OFFICE.

ROBERT G. HANDY, OF BAY CITY, MICHIGAN.

EXPLOSIVE-ENGINE.

1,122,387.

Specification of Letters Patent.

Patented Dec. 29, 1914.

Application filed October 15, 1906. Serial No. 338,960.

To all whom it may concern:

Be it known that I, ROBERT G. HANDY, a citizen of the United States of America, residing at Bay City, in the county of Bay 5 and State of Michigan, have invented certain new and useful Improvements in Explosive-Engines, of which the following is a specification, reference being had therein to the accompanying drawings.

10 This invention relates to new and useful improvements in explosive two-cycle engines.

The invention consists in the matters hereinafter set forth, and more particularly pointed out in the appended claim.

15 In the drawings, Figure 1 is a vertical central longitudinal section through an explosive engine of the open base type one of the cylinders being shown in side elevation. Fig. 2 is a vertical transverse section on the 20 line X—X Fig. 1. Fig. 3 is a horizontal section through the inlet passage on the line Y—Y Fig. 1. Fig. 4 is a horizontal section through the exhaust passage on the line Z—Z Fig. 1.

25 In the drawings, I have shown an explosive engine of the open base type in which 1 is the base, 2 the crank pits, 3 the main bearings, 4 the crank shaft, 5 the connecting rods, 6 the pistons, 7 the wrist pins, 30 8 the cylinders counterbored or enlarged at their lower ends and 9 the supporting pillars connecting the base and cylinders by means of suitable nuts 10.

11 are the cylinder heads, 12 the spark-plugs, 13 the inlet ports, 14 the exhaust ports, a carbureter 26 or like vaporizing means also being provided.

The cylinder 8 comprises an explosion chamber 15 and a compression chamber 16 40 of larger diameter. The compression chamber of one cylinder communicates with the explosion chamber of the other cylinder through a connecting passage 17 communicating with an annular passage 18 in the 45 cylinder, which is in effect a substantially annular discharge mouth although crossed with vertical spaced ribs to prevent the piston rings from springing in.

19 is an annular passage communicating 50 with the exhaust port 14 and provided with

vertical connecting webs 20 like the annular passage 18. As a preferred form of construction, the annular passages 19 are formed in an exterior rib, and the connecting passages 17 are formed by extended integral flanges from these ribs which overlap when the cylinders are in juxtaposition, thereby making the passages very short as if the cylinders were integral, and they may be so made, if desired.

55 The piston 6 is formed at its lower end with a laterally extending flange 21 of a diameter to fit within the enlarged bore of the cylinder forming the compression chamber 16 and at its upper end is provided with a conical head 22 to fit within the explosion chamber and a correspondingly shaped deflector 23 having a central opening 24 and preferably integrally formed with the piston head by webs forming passages 25 connecting the annular inlet passage with the explosion chamber.

60 Having thus fully described the invention it is intended to operate as follows:— On the up-stroke of each piston the gas previously drawn into the annular space of the enlarged portion above the piston end flange is forced through the connecting passage and the head of the other piston into the explosion chamber or main barrel of the cylinder above the piston head, driving out ahead of it through the exhaust ports 19 the products of the previous explosion. On the down-stroke of each piston a fresh charge is drawn into the annular chamber of the 65 counter-bored portion. This gives the regular two-cycle effect of the ordinary engine.

70 Having thus fully described my invention what I claim is:—

75 In an explosive engine, the combination of a pair of cylinders connected intermediate their ends only, each cylinder having a closed upper end, and an open counter-bored lower portion, an inlet port in its wall near the lower end of said counter-bored portion 80 and an exhaust port near the upper end of said portion, an annular inlet passage 85 encircling the cylinder near the head of the counter-bored portion and communicating with the interior of the cylinder through 90

inlet ports and with the upper portion of the counter-bore of the other cylinder through a passage formed in the intermediate connecting portion, with pistons having bodies fitting the upper portion of the cylinders and enlarged lower ends fitting the counter-bored portion of the cylinders, the bodies of the pistons having passages formed in their upper ends adapted to register with the said

inlet ports and throw the same into communication with the body of the cylinder.

In testimony whereof I affix my signature in presence of two witnesses,

ROBERT G. HANDY.

Witnesses:

OTTO F. BARTHOL,
Charles B. Satchwell.
